ALL-PURPOSE GARMENT HANGER

Elizabeth Ciccone Lausch, Garfield, N. J.

Application April 18, 1951, Serial No. 221,684

1 Claim. (Cl. 223—92)

1

This invention relates to a clothes hanger, and more particularly to a hanger for use in displaying articles of clothing, such as women's dresses.

The object of the invention is to provide a garment hanger which is constructed so that the hanger can be used for supporting various types or styles of women's wear, such as dresses.

Another object of the invention is to provide a garment hanger for use in supporting either a halter-type dress, camisole dress, off-the-shoulder dress, strapless dress, or bare midriff dress.

A further object of the invention is to provide a garment hanger which is extremely simple and inexpensive to manufacture.

Other objects and advantages will be apparent during the course of the following description.

In the accompanying drawings forming a part of this application, and in which like numerals are used to designate like parts throughout the same:

Figure 1 is a front elevational view of the hanger of the present invention;

Figure 2 is a side elevational view of the hanger of the present invention;

Figure 3 is a front elevational view of the hanger of the present invention, shown being used for supporting a camisole dress;

Figure 4 is a view similar to Figure 3, but showing the hanger being used for supporting an off-the-shoulder dress;

Figure 5 is a view showing the hanger being used for supporting a strapless dress;

Figure 6 is a view showing the hanger being used for supporting a halter-type dress;

Figure 7 is a view showing the hanger being used for supporting a bare midriff type dress.

Referring in detail to the drawings, there is shown a hanger which is adapted to be used for showing or displaying various types of styles in women's wear. The hanger may be made of any suitable material, such as plastic, and the hanger includes a top portion 10, and arranged intermediate the ends of the top portion 10 and formed integrally therewith or secured thereto is a web 11, Figure 1.

The hanger of the present invention further includes a pair of side portions 12, the side portions 12 extending downwardly and inwardly from the top portion 10. A cross-piece 14 extends between the pair of side portions 12 and is secured thereto in any suitable manner. For supporting the hanger of the present invention, a hook 15 has its shank 16 rotatably or pivotally connected to the web 11 by suitable bearings 17.

2

The upper portion of the hook 15 is adapted to be arranged in engagement with any suitable supporting element or structure.

Extending outwardly from the bottom or lower end of each of the side portions 12 is a bottom portion 20, the bottom portions 20 being curved or shaped arcuately. A pair of cross-bars 18 and 19 are arranged in spaced parallel relation with respect to each other, and the cross-bars 18 and 19 have their ends secured to the lower ends of the side portions 12. A bottom piece 21 extends between the lower ends of the members 20 and is secured thereto.

Arranged on each side of the web 11 is a recess 22, and the top portion 10 is provided with a pair of spaced recesses 23. Arranged adjacent the upper end of each of the side portions 12 is a recess 24, and each of these recesses serves to define a hook, whereby dresses of various styles or designs can be supported as later described in this application.

Referring to Figure 3, the garment hanger of the present invention is shown being used for supporting a camisole dress. The camisole dress 25 is indicated by the numeral 25, and the dress 25 includes a pair of straps 26 that are adapted to be arranged in engagement with the recesses 23. The body or skirt portion 27 of the dress 25 will conform to the lower section 28 of the hanger.

Referring to Figure 4, there is shown an off-the-shoulder dress 29 being supported by the garment hanger of the present invention. The garment hanger has its notches 24 engaged by suitable loops which may be secured to the off-the-shoulder dress 29. The body 30 of the garment 29 will conform to the shape of the lower section 28 of the hanger.

In Figure 5, a strapless dress 31 is shown being supported by the garment hanger, the strapless dress 31 being supported on the bar 14. The body of the dress 31 is indicated by the numeral 32, and the body of the dress 31 will conform in shape to the lower section 28 of the hanger.

In Figure 6, there is shown a halter-type dress 33 being supported by the hanger. Thus, the upper portions of the halter-type dress 33 are arranged in engagement with the notches or recesses 22, while the body 34 of the dress 33 conforms to the shape of the lower section of the hanger. Finally, in Figure 7, there is shown a bare midriff type of dress 35 being supported by the hanger. The bare midriff dress 35 has its upper portion or blouse portion 36 supported

by the top of the hanger, while the skirt or lower portion 37 is supported by the section 29.

From the foregoing, it is apparent that a hanger has been provided which will enable various styles or types of clothing to be efficiently displayed. The hanger of the present invention is especially suitable for use in hotel showrooms and retail stores. Thus, by using the hanger of the present invention, the garments will have more appeal and the hanger of the present invention includes various notches, recesses or other parts whereby a plurality of different types of garments can be supported, as desired. Thus, the hanger of the present invention can be used for supporting a halter dress, a camisole dress, an off-the-shoulder dress, a strapless dress, or a bare midriff dress, as previously described. The hanger of the present invention can be made of molded plastic, and the hooks 15 may be made of metal. If desired, the hanger can be made of light tubing or metal or heavy wire can also be used. By means of the hanger of the present invention, dresses will be able to retain a fresh appearance or look. Further, bathing suits and beach wear can be displayed on the hanger of the present invention. When the hanger is being used, the garments will not accidentally slip therefrom, and also the garment will be easy to handle and such garments can be readily removed from the hanger.

What is claimed is:

A one piece rigid garment hanger having an upper portion, a pair of side portions extending downwardly and inwardly from the outer ends of said upper portion, an outwardly extending arcuate bottom section extending from the lower end of each of said side portions, a web arranged intermediate the ends of said upper portion, and a hook pivotally connected to said web, there being a plurality of notches formed in the outer surfaces of said web, upper and side portions, said garment hanger adapted to selectively support a camisole dress, an off-the-shoulder dress, a strapless dress, a halter-type dress or a bare midriff type dress, said arcuate sections being adapted to provide a support for the waist line of the garment.

ELIZABETH CICCONE LAUSCH.
